WINDOW ACTUATOR

Robert H. Hummert, Dayton, Ohio, assignor to
Standard-Thomson Corporation, Dayton, Ohio,
a corporation of Delaware

Application January 26, 1953, Serial No. 23,291

Term of patent 14 years

(Cl. D10—10)

To all whom it may concern:

Be it known that I, Robert H. Hummert, a citizen of the United States, residing at Dayton, county of Montgomery, State of Ohio, have invented a new, original, and ornamental Design for a Window Actuator, of which the following is a specification, reference being had to the accompanying drawing, forming a part hereof.

Figure 1 is a perspective view of a window actuator with the crank handle depicted in broken lines, showing my new design.

Figure 2 is a side elevational view of the window actuator as viewed from the left of Figure 3.

Figure 3 is a front elevational view of the window actuator.

Figure 4 is a side elevational view of the window actuator as viewed from the right of Figure 3.

Figure 5 is a bottom end view of the window actuator.

The window portion shown in broken lines is for illustrative purposes only. The characteristic features of the design reside in the portion shown in full lines.

I claim:

The ornamental design for a window actuator, as shown and described.

ROBERT H. HUMMERT.
